H. B. TAYLOR

TELEPHONE SWITCH

Filed Aug. 17, 1923

Inventor:
Herbert B. Taylor,
by S. W. Adams, Atty.

UNITED STATES PATENT OFFICE.

HERBERT B. TAYLOR, OF WESTFIELD, NEW JERSEY, ASSIGNOR TO WESTERN ELECTRIC COMPANY, INCORPORATED, OF NEW YORK, N. Y., A CORPORATION OF NEW YORK.

TELEPHONE SWITCH.

Application filed August 17, 1923. Serial No. 657,907.

To all whom it may concern:

- Be it known that I, HERBERT B. TAYLOR, a citizen of the United States of America, residing at Westfield, in the county of Union and State of New Jersey, have invented certain new and useful Improvements in Telephone Switches, of which the following is a full, clear, concise, and exact description.
- 10 This invention relates in general to telephone switches, and specifically to a coordinate switch structure adapted for establishing connections in an automatic or semi-automatic telephone system.
- 15 The object of the invention is to provide a switch of this character in which the operating parts are readily accessible for adjustment or repairs and wherein the number of operating parts is reduced to a minimum.
- 20 In accordance with the foregoing object, a feature of the invention resides in the provision of means whereby sets of multiplied secondary contacts are moved into engagement with sets of primary contacts through 25 the movement of an oscillating or rocking bar.

Another feature resides in the provision of means whereby the primary contacts are moved collectively through the movement of 30 a selecting bar into engageable relation with associated contacting lugs which are movable along the arc of a circle and are adapted to move the primary contacts into position wherein a subsequent movement of the 35 selecting bar is ineffective to disturb the connection already established.

Another feature is the provision of means whereby the free end portions of primary contacts, having a relatively small initial 40 tension, are moved against a stop bar adapted to resist the movement of the active contact in order to secure the requisite contact pressure between the primary contacts and the contacting lugs when they are brought 45 into contact through a movement of the oscillating bar.

Other features and advantages will appear from the following description and by the claims appended thereto, reference being had 50 to the accompanying drawings in which Fig. 1 is a plan view of said switch; Fig. 2 is a right-hand side view thereof; and Fig. 3 is a partial front view of a selecting bar.

Similar reference characters refer to similar parts throughout the several views.

The switch structure shown in Fig. 1 generally consists of a plurality of primary contact sets arranged in coordinate rows on horizontally disposed supports, the contacts of each vertical row being adapted to be moved collectively into engageable relation with multiplied contacting lugs arranged on oscillating bars which are movable through the energization of the associated operating electromagnets.

Each set of primary contacts consists of a plurality of flat contact springs 20, 21, 22 and 23, moulded into individually removable insulating blocks 24 which are held securely on horizontally disposed angle-shaped bars 25 by means of screws 19. The brackets 17 and 18 are generally formed integrally with the plates 26 and 27 and are provided for supporting the bars 25 which are secured at each end on inwardly extending lugs 15 and 16 by means of screws or rivets.

For each vertical row of primary contacts 20, 21, 22 and 23, there is provided a longitudinally movable bar 28 on which an insulating strip 29 is secured by means of rivets 30. Each strip 28 and 29 has a plurality of equally spaced apertures 31 and 32 which register with each other, and through which the free end portions of primary contacts 20, 21, 22 and 23 of each set protrude in juxtaposition with the multiplied contacting lugs 33, 34, 35 and 36. Such multiple contacting lugs are punched out of flat metal strips 37, 38, 39 and 40 and insulatingly arranged on an oscillating bar 41 shown in Figs. 1 and 2. It is to be noted, however, that due to the difference in the dimension of apertures 31 and 32, the active contacts 20, 21, 22 and 23 normally rest on the edge of aperture 32 in the insulating strip 28 in order to insure proper insulation between the sets of primary contacts.

The switch structure may comprise any number of primary contact sets 20, 21, 22 and 23 and any number of sets of multiplied contacting lugs 33, 34, 35 and 36, depending upon the switch capacity desired.

The oscillating bars 41 are each securely arranged on a rotatable bar 42, journaled at each end portion on the flanges 26 and 27 and held loosely in position thereon by means of individually removable hook members 43, which are held in adjusted position on the plates 26 and 27 by means of screws 44. The adjustable stops 45 and 46, are in

tegrally formed with plates 26 and 27 and are provided for holding the oscillating bar 41 and the contacting lugs 33, 34, 35 and 36 served thereby in normal non-operated position with reference to their associated primary contacts 20, 21, 22 and 23, etc. On one end of each bar 42 there is provided a bell crank lever 47 having a pin 48, extending laterally therefrom, in operable relation 10 with a magnet armature 49 adapted to rotate the bar 42 for imparting an oscillating movement to the bar 41 and the contacting lugs 33, 34, 35 and 36 carried thereby in response to each energization of an electro-magnet 50.

For each bar 28, there is provided an armature 51 the free end of which protrudes through an aperture 52 on the top of the bar 28 and is adapted to move the bar 28 and the 20 primary contacts 20, 21, 22 and 23 served thereby in selected position in response to each energization of an operating electromagnet 53. The bars 28 are each slidably arranged in the slots 54 of the cross-bars 55 25 which are rigidly fastened on the top and lower end portions of the plates 26 and 27. For sake of clearness, however, only the top cross-bar is shown in Figs. 1 and 2.

Associated with each horizontal row of 30 primary contacts 20, 21, 22 and 23, there is provided an insulating bar 56 held securely at each end portion on flanges 26 and 27 and which is adapted to resist the upward movement of the primary contacts with which 35 they are associated for securing the requisite contact pressure between the contacting lugs 33, 34, 35 and 36 and the primary contacts 20, 21, 22 and 23, when the bar 41 is moved in operated position. It is to be noted that 40 when the contacting lugs 33, 34, 35 and 36 are moved in operated position, as shown by the lower contact set in Fig. 2, the primary contacts 20, 21, 22 and 23 associated therewith are moved entirely clear of the bar 28 45 against the insulating bar 56, wherein any subsequent movement of the bar 28 is ineffective to disturb the connection already established.

The general operation of the switch mechanism for establishing connections between the primary and secondary contacts consists in moving the selecting bar 28 and the primary contacts 20, 21, 22 and 23 served thereby in selected position as shown by 50 the dotted line in the lower set of Fig. 2. When the primary contacts are moved in selected position through the energization of magnet 53, the oscillating bar 41 is moved in an upward direction wherein the 55 secondary contacts 33, 34, 35 and 36 carried thereby engage the under surface of their associated primary contacts 20, 21, 22 and 23 and move them clear of the selecting bar 28 against the insulating bar 56 provided to resist the movement of primary contacts in 60 65

order to increase the contact pressure between the primary and secondary contacts. The selecting bar 28, however, may be immediately restored to normal to participate in the establishment of other coexisting connections, but the bar 41 and the secondary contacts 33, 34, 35 and 36 carried thereby remain in operated position throughout the duration of the connection. 70

What is claimed is:

1. In a switching device, the combination of primary contact sets, a longitudinally movable bar therefor, an insulating strip arranged on said bar for operatively engaging said contacts, sets of multiple contacts arranged on a circularly movable bar, and means for positioning said primary contacts for engaging said multiple contacts upon the movement of said circularly movable bar. 80

2. In a switching structure, sets of primary contacts, a longitudinally movable bar for supporting and moving said contacts, sets of secondary contacts, a rotatable bar for supporting said sets of secondary contacts, a stationary stop bar disposed adjacent and at right angles to said movable bar, means for moving said first bar to flex said sets of primary contacts into engagement with said stop bar, said stop bar being arranged to limit the initial movement of the primary contacts, and means for moving said rotatable bar to effect an engagement between adjacent sets of primary and secondary contacts, said engagement being effected with a wiping action by the further flexing of said set of primary contacts. 95

3. In a telephone switch structure, the combination of flexible contacts, individually removable insulating supports therefor, 105 slideable bars provided with apertures to permit the protrusion therethrough of said contacts, insulating strips fixedly supported on said bars and provided with other apertures, said second mentioned apertures being arranged to register with first mentioned apertures and to provide means for insulatively supporting said contacts, a stationary stop bar disposed adjacent and at right angles to said slideable bars, rigid contacts, 110 rocking bars supporting said rigid contacts, means for moving said slideable bars to effect an interengagement of said stop bar and flexible contacts, and means for moving said rocking bar to effect an interengagement of 115 said rigid and flexing contacts. 120

4. In a telephone switch structure, the combination of resilient contacts, a slideable bar for moving said contacts, contacting lugs, a rotatable bar for moving said lugs, plates arranged with notches to removably support said rotatable bars, hook members 125 adjustably mounted on said plates and arranged to lock said rotatable bars to said plates, and means for moving said slideable and rotatable bars to effect an interengage- 130

ment of said resilient members and contacting lugs.

5. In a telephone switch structure, the combination of contacting lugs, rotatable supporting bars therefor, supporting plates notched to receive said bars, arms integrally formed with said plates for normally supporting said rotatable bars in a definite position, disengaged contacts, slidable bars for

positioning said contacts, stop bars for limiting the movement of said contacts, means for moving said slidable bars, and other means for rotating said lugs to effect a further movement of said contacts.

In witness whereof, I hereunto subscribe 15 my name this 13th day of August A. D., 1923.

HERBERT B. TAYLOR.
